COMPOSITE WALL AND TABLE FLOWER POT HOLDER

Joseph Lepanto, Kew Gardens, N.Y.

Application May 15, 1957, Serial No. 46,176

Term of patent 14 years

(Cl. D35—3)

Fig. 2 is a bottom perspective view; and
Fig. 3 is a front perspective view with the holder in position for suspension from a wall.

I claim:

The ornamental design for a composite wall and table flower pot holder, as shown.
